COMBINATION KEY SEAT REMOVER AND
VIBRATION DISTRIBUTOR FOR WELL
DRILLING

John McClinton, Houston, Tex.

Application October 23, 1947, Serial No. 781,724

6 Claims. (Cl. 255—73)

1

This invention relates to an apparatus and to a method of removing formations around slots or bores of lesser than drill collar and drill bit diameter such as a bridged portion in the well bore through which it may become necessary to elevate the drill collar and bit of a drilling assembly in withdrawing them out of a well.

This invention also utilizes the same apparatus to minimize the vibratory stresses and strains which travel upwardly from a drilling bit through the drill collar to the tool joints and drill pipe of a drill string.

It often occurs in the drilling of wells by the rotary method where drilling fluid is circulated into and out of the well bore that the drill bit while rotating and moving downwardly by penetrating into the earth may strike an obstacle, usually in the nature of a hard subterranean formation having layers or planes which slant from the vertical. Such an obstacle might be a boulder or crevice which deflects the bit away from the vertical. The bit thus will drill a deflected course determined by the slanted plane or face of the hard formation. However, as the bit and flexible drill pipe rotate, the pull of gravity on the drill string tends to return it to a straightened course, and in time the bit returns to drilling a perpendicularly downward course which may or may not substantially coincide with the general vertical axis which was being drilled prior to the deflection of the bore.

The drilling trades define as a "dog leg" the formation between this curved or deflected bore section and a substantially vertical axis joining the generally vertical bore above the deflection with the generally vertical bore which the bit resumes drilling below it.

As the "dog leg" is formed the drill pipe above the drill collar follows the bit around the bend and rotates in the curved "dog leg" bore. In time the natural tendency of the pipe to straighten and the weight thereof against the inside of the bore wears away the formation in the direction of the generally substantially vertical axis of the bore which the bit is drilling and finally wears a slot into the "dog leg" formation. The pipe thus rotates and moves vertically in such slot or bore which has been cut substantially coincidental with this generally substantially vertical axis of the well bore. The diameter of this new bore is less than that of the bored hole because it has been determined by the diameter of the drill pipe tool joints which have cut the slot as the drill pipe rotated and moved downwardly. Such slot is consequently of smaller

2

diameter than the bore diameter which the bit has drilled.

The bit may have drilled hundreds or even thousands of feet of bored hole below the dog leg before the bit becomes dull or for some other reason is to be withdrawn from the bore hole.

Obviously the larger diameter drill collar and bit cannot be pulled upwardly through the restrictive bore and a certain amount of formation will have to be removed from around the slot or bore which the tool joints have worn as a result of the drill string seeking an aligned axis. In withdrawing the drill string from the well, the drill collar will wedge in the narrow slot between the substantially vertical bore above and below the "dog leg." The trade defines as a "key seat" this formation which has to be removed to permit the upward passage or withdrawal of the drill collar and bit. It follows then that the slot or bore, which the tool joints have cut as the drill string seeks alignment, is called the "key seat" bore.

An object of this invention is to provide an apparatus and a method for removing or enlarging a "key seat" to permit the drill collar and drill bit of a drill string to be withdrawn upwardly therethrough when the drill string is being pulled out of a well.

Another object of this invention is to provide an apparatus and a method which will remove a "key seat" so that the drill collar of the drill string may be drawn upwardly therethrough and pulled out of the well.

Still another object of this invention is to provide an apparatus and a method in which an upwardly and inwardly tapered threaded broach is manipulated to remove a "key seat" by cutting and shearing the formation thereof to enlarge the key seat to a diameter slightly larger than a drill collar.

A further object of this invention is to provide an apparatus and method which minimizes the torque and lift required to be exerted at the surface of the well, by virtue of the combined shearing and cutting of restrictive "key seat" formations by a tapered threaded broach included in the drill string assembly.

Still another object of this invention is to provide an apparatus and method in which an inwardly and upwardly tapered broach has modified acme threads thereon provided with cornered edges, so that the threads can more effectively shear and cut out a "key seat" formation.

Yet another object of this invention is to provide an apparatus and a method of use thereof

3

in which an inwardly and upwardly tapered threaded broach which has become stuck in a restrictive formation, such as a "key seat," can unscrew itself downwardly as the drill string is rotated until gravity pulls the whole drill string downwardly from the "key seat" formation.

A still further object of this invention is to provide an apparatus in the nature of an upwardly and inwardly tapered broach inserted as a flexible element between drill collar and tool joint of the lowest drill pipe section, so as to dampen and minimize the drilling vibrations transmitted upwardly from a drill collar to tool joints and drill pipe of substantially smaller diameter than the drill collar.

Other objects and advantages of the device of this invention will be made apparent through the following description taken in connection with the drawings in which:

Fig. 1 is an elevation, part in section, which shows part of a drill string which is being pulled out of a well, just before the broach is pulled up into the "key seat."

Fig. 2 is a horizontal section of the well bore just above the "dog leg," taken on line 2—2 of Fig. 1.

Fig. 3 is a horizontal section through the "dog leg" above the point of greatest deflection, and after the "key seat" has been worn, taken on line 3—3 of Fig. 1.

Fig. 4 is a horizontal section through the "dog leg" near the point of greatest deflection, and after the "key seat" has been worn, taken on line 4—4 of Fig. 1.

Fig. 5 is a horizontal section taken through the well bore and the threaded broach at its lowest part, taken on line 5—5 of Fig. 1.

Fig. 6 is a sectional elevation which for purposes of illustration shows a "dog leg" of exaggerated curvature and a "key seat" bore of shortened length in the process of being enlarged, and which shows the broach as having just been pulled upwardly until it is about to bind in the "key seat" formation.

Fig. 7 is a horizontal section taken through the well bore above the "dog leg," taken along line 7—7 of Fig. 6.

Fig. 8 is a horizontal section through the "dog leg" above the point of greatest deflection, taken along line 8—8 of Fig. 6.

Fig. 9 is a horizontal section through the "dog leg" near the point of greatest deflection, taken along line 9—9 of Fig. 6.

Fig. 10 is a horizontal section through the drill collar below the "dog leg."

Fig. 11 is an enlarged partial elevation showing the details of the broach thread construction.

Referring in detail to the drawings, the path of drilling is shown as having passed through an ordinary earthen formation 1 and into an exceptionally hard or rocky formation or a deflecting subterranean body 2. Such a formation has deflected the drill bit, not shown, along the deflecting face 3 at an angle to the vertical bore 5. The path from which the general vertical bore 5 of the well is thus deflected is shown as the "dog leg" 4. The general vertical bore 6 is gradually resumed below the "dog leg" 4 after the bit passes by the base 30 of the obstacle or deflecting formation 3.

As the drilling of the bore continues the rotating pipe bearing against the inclined surface 3 on the inside of the bore 4 wears away the formation so that a slot 9 is created by the pipe and the tool joints. The pipe eventually tends to straighten itself and wears away the "key seat" which is de-

4

fined by the bore 7 in the formation at 8, and the slot 9 which has been worn in the formation 1 and 10 between the deflected "dog leg" bore 4 and the bore 7.

A section of the drill string 11 is shown in Fig. 6 as a combination of the drill pipe 12, the tool joint 13, which connects the drill pipe 12 and the broach 14, and the drill collar 15. The bit, not shown, is attached to the end of the drill collar 15. The broach 14, which is both a "key seat" remover and vibration distributor as will be herein-after described, has been inserted in the drill string directly above the drill collar 15. A drill bit, not shown, is attached to the lowest part of the drill collar.

The externally threaded lower pin end 16 of the drill pipe 12 has as shown in Fig. 6 the internally threaded upper end 18 of the tool joint 13 threaded thereon. The externally threaded lower end 17 of the tool joint 13 is threaded into an internally threaded upper portion 19 of the straight-sectioned, unthreaded upper end 20 of the broach 14. This upper broach end 20 is of substantially the same outer diameter as the body 21 of the tool joint 13. The broach 14 has a reduced, externally tapered threaded lower end 22 which is screwed into the internally threaded upper end of the drill collar 15. The drill collar is of larger diameter than the drill pipe to provide weight and rigidity to prevent undue deflection of the bit.

The broach 14 has a tapered threaded section 23 on which the threads decrease in diameter upwardly, the lowest full thread 24 being of a diameter slightly in excess of the outer diameter of the drill collar 15, while the uppermost full thread 25 is only slightly greater than the outer diameter of the upper broach end 20 and the tool joint 13. The broach thread contours are shown as having upper and lower edges 26 and 27 respectively, which are substantially a standard acme profile made dished or concave along the vertical width 28 thereof so as to increase the cutting or shearing action in cutting away the bore 7.

In ordinary drill strings, in point of space and time, breakage is likely to occur where the drill collar, of larger diameter, is joined to the drill pipe of smaller diameter and this breakage is likely to occur when the bit has resumed drilling a substantially vertical course after having finished drilling the course of a dog leg similar to that shown in Fig. 1. This result is obviously due to the fact that the vibratory effects transmitted upwardly from the bit are enhanced in passing up through the portion of the drill collar 15 which is in a substantially vertical bore, and on upwardly into the drill pipe 12, which is whipping about in the "dog leg" 4. And it is pointed out that this breakage occurs at the point of junction of drill pipe and drill collars because of the abrupt change in diameters between the larger drill collar and the comparatively smaller drill pipe.

The insertion of the broach 14 of this invention between drill collar 15 and drill pipe 12 designs to obviate these causes of breakage by providing an element which is tapered over its length 23 from the bottom thread 24 upwardly to the broach end 20. This amounts to a considerable threaded length 23 which provides flexibility as a bridging connection between drill collar and drill pipe. At its point of connection 22 to the drill collar 15 the broach 14 is of essentially drill collar diameter, but, as shown in Fig. 6, even at this point the broach must be of lighter weight and

5

more flexible than the drill collar by virtue of the weight removed over its threaded length 23. As it is tapered down to tool joint diameter at its upper end 20, which is substantially drill pipe diameter, a medium is provided to dampen the stresses and strains transmitted upwardly and to provide a gradient of flexibility between drill collar and drill pipe. Such a construction is especially effective in minimizing the above described tendency toward drill string breakage just after a "dog leg" bore has been drilled.

To move the drill string 11 up through a "key seat" formation 8, and to enlarge the "key seat" bore 7 so as to remove the "key seat," strain is put on the drilling string at the surface of the well and the string is pulled upwardly. If drag is registered at the surface, it is indicative that the broach 14 has moved into binding contact with the "key seat" formation 8.

If the formation is not too hard it may be possible, by exerting both strain and rotational torque at the surface, to move the broach 14 completely up through the "key seat" without it ever becoming bound or stuck in the restrictive formation. The upward strain pulls the upper thread corners 26 into the "key seat" formation 8, and the lead of the threads, when the broach is rotated, tends to shear or cut the formation to enlarge the key seat 7. The threads tend to carry the formation cuttings downwardly into the well bore around the drill collar 15 below the key seat.

When the upward pull on the drill pipe is exerted at the surface of the well, with or without accompanying rotation, the broach 14 is moved up into the "key seat" formation 8 until it wedges therein. The pull may then be slackened off the drill string. If weight alone does not loosen the broach from such wedged position, the drilling string may be rotated in addition. This rotation will cause the broach threads to shear or cut away the formation 8 and move it downwardly. The rotation, aided by the weight of the pipe, drill collar, and bit, will cause the broach to unscrew downwardly so that there is vertically downward motion of the whole drill string. Finally the weight of the drill string below the locality of the binding formation overcomes the binding friction of the formation against the section of broach threads still in contact therewith, and the broach then shears away this binding formation as gravity acts on the drill string weight. This process of pulling up, rotating, slackening on weight, and rotating, may have to be repeated several times before a hard "key seat" is enlarged by removing the formation to permit the upward passage of the drill collar and bit through a sufficiently enlarged "key seat" bore.

The use of drilling mud in the rotary method of drilling wells is a well known and essential part of such operation, the mud being circulated down the drill pipe from the top of the well and up the well bore outside of the drill pipe. As the top thread 25 of the threaded section of the broach is larger in diameter than the broach end 20, and as the bottom thread 24 is larger in diameter than the drill collar 15, mud continuously fills the key seat bore 7 in the space between the broach threads and around the body thereof, and this mud acts as a lubricant between the broach and the key seat formation 8, both when the broach is pulled upwardly, moved downwardly, or rotated. This mud, by gravity, also flows around the drill collar when it is

6

pulled up into the key seat. Thus, this continuous presence of mud insures a lubricant, opposing any condition tending to cause sticking of the broach or drill collar.

The lubricating function played by the mud combines with the manipulation of the broach after the manner in which a "rat tail" file is manipulated in enlarging a hole in wood. By repeating, in the presence of a lubricant, the steps of pulling the broach upwardly into the key seat until it sticks, rotating it to loosen it, and then moving it up and down to shear away the formation between the threads cut by the rotation of the broach, it is possible to remove the formation around the key seat bore to permit the upward passage of the drill collar therethrough. Then the bit on the end of the drill collar, which is of larger diameter than the drill collar, may be worked upwardly through the enlarged bore by rotating the drilling string.

It is also obvious from the construction of the broach that it has a function in wearing away dog leg formations, or any restrictive formations in the bore, as the bit drills downwardly. This results by virtue of the threaded construction of the broach which brings its threads into cutting contact with the dog leg wall in the direction of curvature.

The application of lifting strain, the slackening of the pull, and the rotating of the drill string, are determined by the "key seat" formation, and many combinations and sub-combinations of these forces, aided by the lubricating effect of the mud, may be utilized in employing the apparatus and method of this invention.

Broadly the invention contemplates the insertion of a tapered, threaded element with wider portion downward, into a drill string assembly so that restrictive formations can be cut away by the threads and so that the weight of the drilling string below the element will act to pull the element downward and shear out the formation. Broadly the invention also contemplates the employment of such a tapered element to distribute and dampen vibrations transmitted upwardly through the drill string from the drill bit and drill collar when the bit is drilling.

What is claimed is:

1. A hollow broach comprising a tapered, externally threaded body to be connected into a drill string used in rotating the drill bit in the rotary method of drilling wells where such string includes sections of drill pipe connected with tool joints and drill collars connected to the bit, means on the upper end of said body to connect to a tool joint, means on the lower end to connect to a drill collar, the uppermost thread dimension being of the smallest diameter but slightly greater than the diameter of said tool joint thereabove, the lowermost thread dimension being of the largest diameter and slightly greater than the diameter of said drill collar therebelow.

2. A hollow broach comprising a tapered, externally threaded body to be connected into a drill string used in rotating the drill bit in the rotary method of drilling wells where such string includes sections of drill pipe connected with tool joints and drill collars connected to the bit, means on the upper end of said body to connect to a tool joint, means on the lower end to connect to a drill collar, the uppermost thread dimension being of the smallest diameter but slightly greater than the diameter of said tool

Joint thereabove, the lowermost thread dimension being of the largest diameter and slightly greater than the diameter of said drill collar therebelow, said threads being of substantially acme profile.

3. A hollow broach comprising a tapered, externally threaded body to be connected into a drill string used in rotating the drill bit in the rotary method of drilling wells where such string includes sections of drill pipe connected with tool joints and drill collars connected to the bit, means on the upper end of said body to connect to a tool joint, means on the lower end to connect to a drill collar, the uppermost thread dimension being of the smallest diameter but slightly greater than the diameter of said tool joint thereabove, the lowermost thread dimension being of the largest diameter and slightly greater than the diameter of said drill collar therebelow, said threads being of substantially acme profile with the vertical widths thereof dished.

4. A hollow broach comprising a tapered, externally threaded body to be connected into a drill string used in rotating the drill bit in the rotary method of drilling wells where such string includes sections of drill pipe connected with tool joints and drill collars connected to the bit, means on the upper end of said body to connect to a tool joint, means on the lower end to connect to a drill collar, the uppermost thread dimension being of the smallest diameter but slightly greater than the diameter of said first means and said tool joint thereabove, the lowermost thread dimension being of the largest diameter and slightly greater than the diameter of said second means and said drill collar therebelow.

5. A hollow broach comprising a tapered, externally threaded body to be connected into a drill string used in rotating the drill bit in the rotary method of drilling wells where such string includes sections of drill pipe connected with tool joints and drill collars connected to the bit, means on the upper end of said body to

5 connect to a tool joint, means on the lower end to connect to a drill collar, the uppermost thread dimension being of the smallest diameter but slightly greater than the diameter of said tool joint thereabove, the lowermost thread dimension being of the largest diameter and slightly greater than the diameter of said drill collar therebelow, said tapered threads being cut to a sizeable profile to remove sufficient stock from said body to render said broach substantially flexible.

6. A key seat remover tool to be rotated by a drill pipe in rotary drilling comprising a tapered tubular body, a pipe connection at each 15 end of said body to position said body in the drill pipe with the smaller end of the taper up, a coarse shearing thread on the periphery of said body so that as the tool is rotated, raised, and lowered, in a restricted area in a well bore 20 such area will be enlarged by the movement of such coarse thread and the surging of well liquid in the area to lubricate the tool.
